SHIELDING DEVICE

John M. Bowman, Philadelphia, Pa., assignor to
 Philco Radio & Television Corporation, Phila-
 delphia, Pa., a corporation of Delaware

Application February 27, 1935, Serial No. 8,577

4 Claims. (Cl. 250—27.5)

This invention relates to shielding devices for electrical apparatus. More specifically the invention relates to shielding devices for vacuum tubes of radio receivers.

One object of the invention is to provide a device which is easy and economical to manufacture, particularly in quantity production, and which is efficient in operation and serves to hold the vacuum tube firmly, thus preventing microphonic action of the tube due to vibration.

Another object of the invention is to provide a device which may be easily manipulated and applied to a vacuum tube even though there may be some mismatch of the elements.

A further object of the invention is to provide a device composed of a plurality of parts constructed so that the parts may be properly attached together regardless of slight misfit thereof and which assures good electrical contact of the parts.

A preferred form of the device is illustrated in the accompanying drawing, wherein

Fig. 1 is an elevational view of the lid of the device;

Fig. 2 is an elevational view of the shell;

Fig. 3 is an elevational view of the base;

Fig. 4 is a plan view of the base;
 Fig. 5 is an elevational section of the device in cooperative relation with a vacuum tube; and
 Fig. 6 is a sectional view along line 6—6 of

Fig. 4.

Referring to the drawing the device comprises a body or shell 1, a lid 2, and a base 3. These parts may be made of terneplate or any other material which is satisfactory. The body 1 is substantially or generally square in cross-section with rounded corners. It may be made in conventional manner from a flat piece of material. The four corners at the bottom of the body are slightly flared outward, as at 4, and this together with the deformability of the body facilitates placing it on the base even though there may be some slight misfit. A small rim 5 may be formed at the bottom of the body to stiffen it and make it fit tightly over the base.

Preferably, there are small centrally located holes 6 in the sides of the body to provide ventilation. Any desired number of these holes may be provided but it is desirable that one hole in each side be located at the point where the widest portion of vacuum tube is located when in place, as shown at 7 in Figs. 5 and 6. The cross-sectional area of the body 1 is such that the tube fits snugly therein with the widest portion of the glass envelope 8 of the tube seated

in the openings of the body, as shown in Fig. 6. This serves to hold the tube securely and prevents vibration or rattling of the same with its consequent microphonic action. Due to the deformability of the body permitted by its square cross-sectional form, it adjusts itself to the tube when necessary thereby assuring the desired tight fit.

The body 1 may be provided with a recess or slot 9 to allow entrance of a conductor attached to the grid terminal 10 at the top of the tube. A small ridge 11 may be indented around the top of the body to hold the lid or cover firmly in place. The top edge of the body is preferably turned over, as at 12 to eliminate sharp exposed edges. The lid 2 may be formed of extruded terneplate and is adapted to fit snugly over the top of the body 1. It is not essential, however, that a lid be used.

The base 3 may also be extruded from terneplate. This member is of the same contour as the body and is adapted to fit snugly inside the lower part of the body, as shown in Fig. 5. The base is provided with rounded corners and has diagonally opposite corner indentations 13 to provide apertured mounting ears 14. These corner indentations also provide space which allows for mismatch between the body and base. The large aperture 15 of the base is adapted to receive the base 16 of the vacuum tube. The rim formed by the hole 15 in the base serves to stiffen the base and thus hold the shell 1 in place. This tight fit also provides good electrical contact between the shell and the base, thus assuring that the metal shell will act as an effective electrical shield.

Various changes or modifications are of course possible and are to be deemed within the scope of the invention.

I claim:

1. A shielding device for electrical apparatus, such as vacuum tubes, comprising a relatively rigid metallic base of non-circular cross-section having corner indentations, and a body or shell of similar cross-section adapted to fit over said base and formed of deformable metallic material, so that said shell fits snugly over the apparatus with which it is used and also fits snugly over said base notwithstanding slight misfit of the said elements, said indentations providing space which permits greater deformability of said shell in fitting over said base.

2. A shielding device for electrical apparatus, such as vacuum tubes, comprising a relatively rigid metallic base of non-circular cross-section

- having opposed corner indentations and means at said indentations for mounting said base, and a body or shell of similar cross-section adapted to fit over said base and formed of deformable metallic material, so that said shell fits snugly over the apparatus with which it is used and also fits snugly over said base notwithstanding slight misfit of the said elements, said indentations providing space which permits greater deformability of said shell in fitting over said base.
3. A shielding device for electrical apparatus, such as vacuum tubes, comprising a relatively rigid metallic base of generally square cross-section having rounded corners with opposed corner indentations and means at said indentations for mounting said base, and a body or shell of similar cross-section having rounded and flared corners, adapted to fit over said base and formed of deformable metallic material, so that said shell fits snugly over the apparatus with which it is used and also fits snugly over said base not-

withstanding slight misfit of the said elements, said indentations providing space which permits greater deformability of said shell in fitting over said base.

4. A shielding device for a vacuum tube, comprising a relatively rigid metallic base of generally square cross-section and having an opening for reception of the tube base, said base having opposed corner indentations and means at said indentations for mounting said base, and a metallic shell of similar cross-section deformable throughout its length and adapted to fit over said base and having openings in its sides to seat the widest portion of the tube, so that said shell fits snugly over the tube and also fits snugly over said base notwithstanding slight misfit of the said elements, said indentations providing space which permits greater deformability of said shell in fitting over said base.
